Patented Aug. 25, 1925.

UNITED STATES PATENT OFFICE.

JOHN W. COWELL, OF LOS ANGELES, CALIFORNIA.

MOLD FOR MAKING TILE.

No Drawing.

Application filed May 17, 1924. Serial No. 714,097.

To all whom it may concern:

Be it known that I, JOHN W. COWELL, a citizen of the United States, residing at Los Angeles, in the county of Los Angeles and State of California, have invented new and useful Improvements in Molds for Making Tile, of which the following is a specification.

My invention relates to molds for forming objects, particularly artificial tile, out of plastic materials, such as plaster of Paris, cement and the like.

The main object of my invention is to provide a mold for casting tile and similar articles, which will yield a perfectly smooth cast, free from broken corners or edges and like defects.

Other objects and advantages will appear hereinafter and while I show herewith and will describe a preferred form of construction, I desire to be understood that I do not limit my invention to such preferred form but that various changes and adaptations may be made therein without departing from the spirit of my invention as herein-after claimed.

Referring to the drawings which accompany this specification and form a part thereof:

30 Fig. 1 is a plan view of the metal blank from which my mold is formed.

Fig. 2 is a plan view of the mold after it has been formed out of the blank shown in Fig. 1.

35 Fig. 3 is a sectional view through the mold shown in Fig. 2.

Fig. 4 is an enlarged view in perspective of one corner of the mold shown in Fig. 2.

40 Fig. 5 is a sectional view of an inverted mold and a tile contained therein, illustrating one method of discharging a cast from the mold.

The mold is made of thin sheet metal, preferably of a springy character. Blanks of any suitable size and shape are cut out of the sheet metal and these are bent into the desired form. The blank shown in Fig. 1 is intended for a square and comparatively thin tile. Corner notches 10 are made to provide for side walls and rim flanges, leaving a central square 11 to serve as the bottom of the mold. The side wings 12 thus formed are bent upward along dotted lines 13, at right angles to the bottom, to form vertical walls 14, which meet at their ends, thus forming loose corners 15, which may be

sprung apart readily when the cast is to be discharged from the mold.

Another right angled bend is made along dotted lines 16 of side wings 14 to form horizontal rim flanges 17 and creases 18 are made near the outer edge of these rim flanges. These creases are made downward so as to form shallow grooves 19 in the upper sides of the flanges.

In using the molds thus formed, they are filled with any plastic material employed for making tile and like objects, and are allowed to stand until the material hardens or sets sufficiently to be removed.

In removing the cast the mold is inverted and supported on the outer edges of the flanges. Downward pressure exerted on the bottom then springs the walls apart opening the corners admitting air and allowing the cast to drop out. With small molds this may be done readily by the hands, holding the flanges with the fingers and pressing down with the thumbs. With larger molds a device as shown in Fig. 5 may be employed.

A hole 20, slightly larger than the cast to be removed, may be made in a table top 21; guide strips 22, spaced so as to admit the mold flanges and allow for their expansion, may be fixed around the opening, and resting strips 23 adapted to engage with grooves 19 of the mold flanges, may be fixed around the opening inside the guide strips 22. The mold and cast may then be inverted and placed over the hole as shown. Downward pressure on the bottom in this position, as is evident, will spring the walls of the mold apart and allow the cast to drop through the table.

Having thus illustrated and described my invention, I claim:

1. A mold for making face tile, as for floors, walls, mantels and the like, comprising a shallow container having a flexible bottom and flexible walls formed integral therewith, said flexible walls extending upwardly at right angles from said bottom and meeting at their ends to form loose corners, which may be sprung open to release the cast.

2. A mold for making face tile, as for floors, walls, mantels and the like, comprising a shallow container having a flexible bottom and flexible walls formed integral therewith, said flexible walls extending upwardly at right angles from said bottoms

and meeting at their ends to form loose corners, and lateral outwardly turned flanges formed integral with said flexible walls, whereby said walls may be sprung outwardly to release the cast.

3. A mold for making face tile as for floors, walls, mantels and the like, comprising a shallow, substantially square metal container having a flexible bottom and flexible walls formed integral therewith, said flexible walls extending upwardly at right

angles from said bottom and meeting at their ends to form loose corners and outwardly turned flanges formed integral with said flexible walls at right angles thereto, whereby said walls may be sprung outwardly to release the cast, said flanges being creased to form a groove on their upper side which is adapted to engage with cooperative means for springing said walls. 15

JOHN W. COWELL.

Certificate of Correction.

It is hereby certified that in Letters Patent No. 1,550,950, granted August 25, 1925, upon the application of John W. Cowell, of Los Angeles, California, for an improvement in "Molds for Making Tile," errors appear requiring correction as follows: Page 1, following the title, strike out the words "No Drawing." One sheet of drawings containing Figures 1 to 5, inclusive, attached hereto, should appear as part of the Letters Patent; and that the said Letters Patent should be read with these corrections therein that the same may conform to the record of the case in the Patent Office.

Signed and sealed this 3d day of November, A. D. 1925.

[SEAL.]

KARL FENNING,
Acting Commissioner of Patents.
